UNITED STATES PATENT OFFICE.

JOHN T. PERO AND LLEWELLYN P. JONES, OF PARSONS, PENNSYLVANIA.

SAFETY-CATCH FOR MINING-CAGES.

1,178,942.

Specification of Letters Patent. Patented Apr. 11, 1916.

Application filed June 11, 1915. Serial No. 33,531.

To all whom it may concern:

Be it known that we, JOHN T. PERO and LLEWELLYN P. JONES, citizens of the United States, residing at Parsons, in the county 5 of Luzerne and State of Pennsylvania, have invented certain new and useful Improvements in Safety-Catches for Mining-Cages, of which the following is a specification.

Our invention has relation to certain new 10 and useful improvements in safety catches for mining cages and the like and has for its primary object, the provision of a form of safety catch which may be readily applied to the types of mining cages now in general 15 use without the necessity of materially altering the construction of the same.

Another object of the invention resides in the provision of a safety catch of this character in which will be included guide en- 20 gaging members and also improved and novel mounting and operating means for the guide engaging members.

With these and other objects in view, the invention consists in the novel construction, 25 combination and arrangement of parts, as will be hereinafter more in detail described and the asserted novelty pointed out in the appended claims.

In the accompanying drawings which 30 clearly and fully illustrate our invention, Figure 1 is an elevation of the complete device applied to a mine cage of conventional form, and showing the operative parts of the invention in normal position, parts of 35 the cage and the guides for the same being broken away, in this view. Fig. 2 is an elevation at right angles to Fig. 1, with the operative parts of the invention in normal position. Fig. 3 is an enlarged detail elevation of one of the guide engaging members looking at the inner face of the same. Fig. 4 is an enlarged elevation of the supporting 40 screw for one of the guide engaging members, removed. Fig. 5 is an end elevation of 45 the same. Fig. 6 is an enlarged detail elevation of one of the pawls removed. Fig. 7 is a vertical section through the same, on the line 7—7 of Fig. 6, and, Fig. 8 is an enlarged 50 elevation of one of the pawl supporting screws, removed.

Referring more particularly to the drawings in which similar reference characters designate corresponding parts throughout the several views, A designates the vertical

guides, between which moves the mine cage 55 B, of conventional form, and which is pro- vided with the transverse side arms C. The cage B has corner bearing blocks D, in op- posite upper corners of its frame, provided with upwardly directed slots D', the pur- 60 pose of which will readily appear as the de- scription proceeds.

Secured against the upper and lower faces of the top of the cage and at the center thereof are the reinforcing plates E and E'. 65 The depending pins F are carried by the plate E' and coöperate with the pins F pro- jecting upwardly from the movable plate E'', to support the operating and normally compressed springs G, engaged around said 70 pins F and F'. The movable plate E'' is carried in a suitable manner upon the lower end of the central cable shaft H, slidably engaged through the top of the cage and through the reinforcing plates E and E' and 75 is spaced from the plate E' by the pins F and F' and also by the spacing blocks upon the cable shaft H.

Rigid with and projecting outwardly from the opposite ends of the movable plate E'', 80 are the pairs of outwardly and upwardly directed arms i', i' to the upper free ends of which are pivoted the inner ends of the rock arms I, mounted for rocking move- 85 ment upon the stationary shafts I', secured in the slots D', previously mentioned. The outer ends of the rock arms I are bent down- wardly and outwardly and carry the studs I'', which are engaged through the elon- 90 gated vertical slots j' in the flattened upper ends of the depending rods J, on opposite sides of the guides A, as clearly shown in Figs. 1 and 2 of the drawings. The studs also have mounted thereon, the pawl releas- 95 ing rods K.

The lower forked ends L of the depend- ing rods J are pivoted to the upper corners of the triangular guide gripping members L', which have gripping teeth L'', on their inner faces, arranged in off-set rows as clear- 100 ly shown in Fig. 3, while the ratchet teeth L''' are located upon the outer faces of said triangular guide gripping members L'.

The lower ends of the pawl releasing rods K are bent outwardly at an angle and ex- 105 tended through the angular guide plates M, carried by the cross arms C, and are then engaged in the recesses N' in the upper

edges of the pawls N to retain the latter in their outermost or inoperative positions, as clearly shown in Fig. 2.

The triangular guide gripping members L' are provided with inclined elongated slots O, through which are engaged the smooth body portions of the supporting screws P, secured in the side arms C, in any suitable manner, the smooth body portions 10 of said supporting screws P being flattened upon opposite sides, as clearly shown in Figs. 2, 4 and 5, to prevent turning of either the screws P or the gripping members L'. It will also be evident that as the slots O and 15 the heads of the screws P are beveled, the gripping members L' will be prevented from working the screws P, during the operation of the parts.

The pawls N are mounted upon the pawl 20 supporting pins Q, securing in the side arms C, outwardly of the supporting pins P, turning of said pins Q in the side arms C being prevented, by means of longitudinal ribs Q', formed preferably on the small 25 threaded ends of said pins Q, while turning or swinging movement of the pawls N, in either direction, upon the pins Q, is limited by means of the short longitudinal ribs Q'', projecting inwardly from the heads of said 30 pins Q and engaged in the recesses N'' of the pawls N.

Under normal conditions all of the parts of the device are in the positions shown in the drawings. Should the cable break however, or should the strain upon the cable 35 shaft H be relieved, owing to an accident or any other cause, the springs G will expand forcing downwardly the inner ends of the rack arms I and causing the latter to 40 swing upon the rock shafts I', to raise the outer ends of said rock arms I and draw upwardly the depending rods J. This causes an upward and inward movement of the gripping members L', until the gripping 45 teeth L'' thereof bite into the opposite sides of the guides A and thereby prevent movement of the cage B. During this operation, the rods K are also drawn upwardly and away from the pawls N, permitting the latter to swing over into engagement 50 with the ratchet teeth L'', to lock the gripping members L' in their operative positions to prevent them from moving away from the guides A. It therefore will be 55 evident that the cage B will be securely locked against movement, until the cable is replaced and the cable shaft H drawn up-

wardly to again compress the springs G and return the operative parts of the device to their normal positions. 60

When tension is again put on the cable H, the rods K are pushed downwardly and release the pawls N, thus permitting the gripping members L' to be forced out of gripping relation with the guides when the pins 65 I'' reach the ends of the slots in the members J.

While the preferred embodiment of the invention has been shown and described, it will be understood that minor changes in the 70 details of construction and arrangement of parts may be made within the scope of the appended claims without departing from the spirit of the invention or sacrificing any of the advantages thereof. 75

What is claimed is:—

1. The combination with a mine cage and guides for the same, of cross arms carried by said cage, guide gripping members slidably mounted upon said cross arms, a cable 80 shaft for said mine cage, connections between said cable shaft and said guide gripping members for forcing the latter into engagement with said guides upon movement of said cable shaft in one direction 85 through said mine cage to lock said mine cage against movement, means for locking said guide gripping members against said guides, and means for releasing said guide gripping members upon movement of said 90 cable shaft in the reverse direction through said mine cage.

2. The combination with a mine cage, guides, a cable shaft adapted for limited sliding movement through said mine cage, 95 and cross arms carried by said mine cage; of guide pins carried by said cross arms, gripping members slidably mounted upon said guide pins, pawl members pivoted upon said cross arms, means connected with said 100 cable shaft to force said gripping members into engagement with said guides upon sliding movement of said cable shaft in one direction, said pawl members being adapted for automatic engagement with said gripping members to lock the latter against said guides, and means for swinging said pawl members away from said gripping members to release the latter, upon movement of said cable shaft in the reverse direction. 105 110

In testimony whereof we affix our signatures.

JOHN T. PERO.
LLEWELLYN P. JONES.
